UNITED STATES PATENT OFFICE.

WALTER L. FAIRCHILD, OF NEW YORK, N. Y.

APPARATUS FOR HANDLING HEATED MOLDS FOR TIRES, TUBES, AND THE LIKE.

Application filed February 24, 1925. Serial No. 11,008.

This invention relates to a new and improved apparatus for handling heated molds for tires, tubes and the like, and one of the objects of the invention is to provide a new and improved pneumatically controlled and operated apparatus for moving the mold as a whole, and also for moving the sections of the mold relatively to each other.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings, wherein I have illustrated a preferred form of embodiment of my invention:

Figure 1 is an elevational view, showing my improved apparatus, showing the mold sections in open position, and also showing in dotted lines the position in which it is desired to move the mold during the vulcanizing operation.

Figure 2 is a similar view, showing the mold in closed position, ready to be opened to insert the article to be vulcanized therein.

Figure 3 is a view in horizontal section, showing one of the controlling valves employed in this apparatus.

Figure 4 is a view similar to Figure 3, showing the valve in a different position; and

Figure 5 is a top plan view of one of the controlling cylinders, said view being taken substantially on the line 5-5 of Figure 2, looking in the direction of the arrows, or on line 5'-5' of Figure 1, looking in the direction of the arrows.

Referring now to the drawings, wherein similar reference characters refer to similar parts throughout the several views thereof, the reference numeral 1 denotes one of the standards for supporting the mold, the latter being mounted upon a base 2, it being understood that a similar stem is provided upon the opposite end of the base, so that the lower section 3 of the mold 4 may be mounted upon trunnions 5 between said standards, whereby the mold may be rotated to the positions shown in the drawings. The upper mold section 6 is provided with a bracket arm 7, which is pivoted as by means of the

rod 8 to a bracket 9 extending rearwardly from the lower mold section 3. This pivotal construction permits the upper section 6 to be swung upwardly, as illustrated in Figure 1, whereby the article to be vulcanized may be readily inserted or removed from the lower section 3 of the mold.

In the present embodiment of my invention, the same is particularly adapted for vulcanizing pneumatic tubes for vehicle tires and the like.

The reference numeral 10 denotes a cylinder, one end of which is pivotally mounted at 11, to the base 2 of the machine, said cylinder being provided with a piston, the rod 12 of which is journaled at 13 to the rod 8, which forms the pivotal connection between the mold sections.

Leading into the cylinder 10 is an air conduit 14, which extends from a suitable source of air pressure, said conduit being provided with a valve 15, having an operating handle 16, which may be connected to a pull-chain 17, it being understood that a spring, not shown, will be employed for closing the valve. The interior construction of the valve 15 is illustrated in Figures 3 and 4.

It will be seen that the valve casing is provided with a passageway 18 extending entirely therethrough, and with a branch passageway 19 which leads to the atmosphere. The valve 20 is provided with a straight passageway 21, and with the branch passageway 22, which leads into the passageway 21.

It will be seen that when parts of the valve are in the position shown in Figure 4, the source of air pressure will be connected with the cylinder above the piston in the cylinder 10, whereby the piston will be forced downwardly, causing the rod 12 to swing the mold upon its trunnion 5 to the position shown in the dotted lines of Figure 1 of the drawings.

In this connection it will be noted that the mold proper is so mounted between its points of pivotal support that the part of the mold in front of its trunnions is heavier than the part thereof located to the rear of said trunnions, whereby the mold at all times is urged to a horizontal position by gravity. When it is desired to permit the mold to return to its normal or horizontal position, the valve is operated to the position shown in Figure 3, whereby the pressure

of the cylinder is released to the atmosphere through the passageways 22 and 19. Thus the piston will freely move upwardly as the mold returns to its horizontal position by 5 gravity.

The reference numeral 23 denotes a cylinder pivotally mounted as at 24 to a bracket 25 supported upon the upper end of the frame. This cylinder is provided with a 10 piston having a piston rod 26, the outer end of which is pivotally connected at 27 to a bracket 28 mounted upon the forward end of the upper mold section 6. The reference numeral 29 denotes a conduit, one end of 15 which leads from a suitable source of air pressure and the other end leads through a valve 30 to the cylinder 23, below the piston therein, so that when air is admitted into the cylinder 23, the piston will be 20 moved upwardly within the cylinder, lifting the upper section 6 of the mold, as shown in Figure 1 of the drawings. The valve 30 is constructed similarly to the valve illustrated in Figures 3 and 4, that is to say, 25 the conduit 29 may be connected directly with the cylinder, shutting off the vent 31, or the interior of the cylinder 23 below the piston may be connected to the atmosphere, through the vent 31, the air pressure to the 30 cylinder through the conduit 29, being at this time shut off.

The valve 30 may be likewise operated by a pull-chain 32, a spring not shown being employed to restore the valve to the position 35 shown in Figure 1 of the drawings. The cylinder 23 at its upper end is provided with a head 33 having the vent apertures 34, and the cylinder 10 is similarly constructed at its lower end.

40 Having thus described the construction of this embodiment of my invention, the operation thereof, which should be largely obvious from the above description, may now be understood.

45 Assuming the parts to be in the position shown in Figure 2 of the drawings, and it is desired to open the mold to insert therein, or remove therefrom, the tube which is to be, or has been, subjected to the vul- 50 canizing process; the valve 30 is manipulated so that air is forced into the cylinder 23, whereupon the piston rod 26 will move upwardly, thereby swinging the mold section 6 upwardly, as indicated in Figure 1.

55 When it is desired to permit the mold section 6 to return to the horizontal position, the valve 30 will again be manipulated to connect the interior of the cylinder 23 through the vent 31 to the atmosphere and 60 disconnect it from air pressure, whereupon section 6 will swing downwardly to the position shown in Figure 2. At this point it may be noted that the vent of the upper end at the cylinder 23 permits of this operation.

65 When it is desired to swing the entire

mold bodily to the position indicated by the dotted lines of Figure 1, the valve 15 will be manipulated to connect the conduit 14 with the interior of the cylinder 10, whereupon the piston in said cylinder 10 will be 70 forced downwardly, causing the piston rod 12 to move in a corresponding direction, whereupon the mold will be swung to the position shown in dotted lines. In this connection it will be noted that the valve 30, 75 which controls the admission of air into the cylinder 23 and also the exhaust, will be in the position last above described. In other words, the interior of the cylinder 23 will be connected with the exhaust. In this 80 position it will be seen that the piston of the cylinder 23 is free to move upwardly or downwardly, as the mold as a whole is swung upon its trunnions, by its operating mechanism.

85 During this operation it will be noted that the cylinder 23 and its associated parts will take the position indicated in the dotted lines in Figure 1 of the drawings.

Thus it will be seen that this mechanism 90 is especially well adapted to move the heated molds and the movable sections thereof expeditiously without danger of the operator coming in contact with the heated parts of the mold.

95 This apparatus also reduces to a minimum the expenditure of manual labor in operating the mold, permitting the mold or parts thereof to be freely moved by the operator without leaving his position in front of the 100 machine.

The arrangement described provides not only for the ready opening and closing of the mold, but it enables the whole mold, during vulcanization, to be moved into any desired position or to be intermittently moved from one position to another. This is a matter of importance because the tendency of water of condensation to collect at a given point hampers perfect vulcanization by tending to prevent proper cure at the point or 110 points of collection. This is substantially overcome by moving the mold into an angular position and, especially, by occasionally changing the position of the mold during 115 vulcanization.

120 It will be understood that various changes may be resorted to in the form, construction and arrangement of the several parts without departing from the spirit and scope of my invention; hence, I do not intend to be limited to the details herein shown and described except as they may be included in the claims.

125 Having thus described my invention what I claim as new and desire to secure by Letters Patent is:

1. Apparatus of the character described comprising, a support, a mold pivotally mounted in said support, said mold compris- 130

ing hinged sections, means connected to one section for swinging the same to open and close the mold, and means operatively connected to both sections for swinging the 5 whole mold on its pivotal mounting, both said means being automatically operated.

2. Apparatus of the character described comprising, a support, a mold pivotally mounted in said support, said mold comprising hinged sections, means connected to one 10 section and to the support above the pivotal mounting for swinging the section to open and close the mold, and means operatively connected to both sections and to the support below the pivotal mounting for swinging the 15 whole mold on its pivotal mounting, both said means being automatically operated.

3. Apparatus of the character described

comprising, a support, a mold pivotally mounted in said support, said mold comprising hinged sections, a fluid operated cylinder connected to one section and to the support above the pivotal mounting for swinging the section to open and close the mold, and a second fluid operated cylinder operatively connected to both sections and to the support below the pivotal mounting for swinging the whole mold on its pivotal mounting, the connection of said cylinders to the support being pivotal whereby straight line operation of the cylinders with respect to the mold can be maintained in various positions of the mold. 20 25 30

In testimony whereof, I affix my signature.

WALTER L. FAIRCHILD.
